J. C. LOCKHART,
LIQUID FUEL BURNER,
APPLICATION FILED OCT. 1, 1919.

1,344,414.

Patented June 22, 1920.

Inventor

J. C. Lockhart

By Franklin D. Hough

Attorney

UNITED STATES PATENT OFFICE.

JOSEPH C. LOCKHART, OF WELLINGTON, KANSAS.

LIQUID-FUEL BURNER.

1,344,414.

Specification of Letters Patent. Patented June 22, 1920.

Application filed October 1, 1919. Serial No. 327,776.

To all whom it may concern:

Be it known that I, JOSEPH C. LOCKHART, citizen of the United States, residing at Wellington, in the county of Sumner and State of Kansas, have invented certain new and useful Improvements in Liquid-Fuel Burners; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in liquid fuel burners, and comprises a simple and efficient device of this nature so constructed as to enable crude or other oils to be heated to the point of vaporization before being ignited.

The invention comprises a simple and efficient device of this nature having various details of construction, combination and arrangement of parts which will be hereinafter fully described, shown in the accompanying drawings and then specifically defined in the appended claim.

My invention is illustrated in the accompanying drawings which, with the numerals of reference marked thereon, form a part of this application, and in which:

Figure 1 is a view in elevation, parts in section, and

Fig. 2 is a top plan view.

Reference now being had to the details of the drawings by numerals:

1 designates a generator pan and 2 a vertically disposed generator pipe leading through said pan and to the lower end of which a tube 3 is connected, and through

which oil may be conveyed to the generator pipe from the tank 4, said tube having a suitable valve 5 therein for regulating the supply of oil. Said generator pipe has a T 6 45 connected to its upper end, and 7 and 8 designate laterally extending pipes leading in opposite directions from the T, and upon the horizontally disposed portion of each pipe 7 and 8 is mounted a flash plate 9 directly over the jet end 10 of the pipe 8.

A hollow imperforate tube 11 is mounted inside the generator pipe and constitutes an extension of the pipe 3 and terminates at the tip, or jet end, 10, by which construction the oil is vaporized and a clean, clear blaze is produced at the flash plates.

In operation, oil is poured into the generator pan and ignited for the initial vaporizing of the oil as it issues from the burner 60 jets, after which the oil will be sufficiently heated from the heat generated from the burners to cause the same to be thoroughly vaporized as it burns against the flash plates.

What I claim to be new is:

An oil burner comprising a generator pan, a generator pipe passing through said pan and having branching pipes extending in opposite horizontal directions above said pan, thence downward, and thence inward, 70 and terminating in a jet, a conduit leading to said generator pipe from a source of liquid fuel supply, flash plates depending from said branch pipes and positioned over said jet ends, and a hollow imperforate tube 75 extending through said pipes and constituting an extension of said conduit and terminating at said jet ends.

In testimony whereof I hereunto affix my signature.

JOSEPH C. LOCKHART.
